Primary Examiner — Natasha Vujcic(74) *Attorney, Agent, or Firm* — James Joyce; Godfrey & Kahn, S.C.(57) **CLAIM**

The ornamental design for a light fixture, as shown and described.

DESCRIPTION

FIG. 1 is a top front perspective view of a light fixture showing our new design;

FIG. 2 is a bottom rear perspective view thereof;

FIG. 3 is a front view thereof;

FIG. 4 is a rear view thereof;

FIG. 5 is a right side view thereof;

FIG. 6 is a top view thereof;

FIG. 7 is a left side view thereof; and,

FIG. 8 is a bottom view thereof.

The broken lines in the figures show portions of the light fixture that form no part of the claimed design.
